UNITED STATES PATENT OFFICE.

CHARLES W. BROCKETT, OF BROOKLYN, NEW YORK, ASSIGNOR TO W. R. OSTRANDER & COMPANY, OF NEW YORK, N. Y., A CORPORATION OF NEW YORK.

ELECTRIC SWITCH.

1,274,674.

Patented Aug. 6, 1918.

Application filed October 31, 1917. Serial No. 199,418.

To all whom it may concern:

Be it known that I, CHARLES W. BROCKETT, a citizen of the United States of America, residing at Brooklyn, New York, 5 have invented a new and useful Electric Switch, of which the following is a specification:

This invention relates particularly to switches of the key socket type and the objects of the invention are to provide a simple and effective construction which will enable the ready assemblage of such switches within the ornamental shells of lighting fixtures, or husks, as they are commonly 10 termed.

Another object is to provide a self-adjusting form of contact for the spring switch arm which will compensate for variations in the size and relation of the parts.

In accordance with this invention I construct the switch with a detachable key having a projecting angular sided stem for engagement in a similar shaped socket provided in the end of the switch operating 25 spindle, said parts preferably having a tapered driving fit so that the key may be firmly attached to the spindle by a simple driving blow.

Another feature of the invention is the 30 making of the keys with a projecting angular sided stem of standard length which can be cut shorter to meet particular requirements and the provision of insulating bushings which can be cut to proper length to 35 cover the exposed portion of the stem between the base of the key and the end of the stub spindle.

Variations in size and fit, etc., of the parts 40 are automatically compensated for by making the relatively stationary contact with which the movable spring contact engages, of spring material and held beneath the foot of the circuit terminal so that it may yield to compensate for variations and inequalities.

The various features of construction will appear more fully as the specification proceeds and will be made clear by a consideration of the accompanying drawing which 50 illustrates the invention embodied in a practical and preferred form.

In said drawing:—

Figure 1, is a part sectional view of one 55 form of the switch as embodied in a husk type of fixture.

Fig. 2, is a sectional view taken substantially on the plane of the line 2—2 of Fig. 1.

Fig. 3, is a detached perspective view of the joint between the detachable key and the switch operating stub spindle. 60

The particular switch illustrated is of an approved type comprising a two-part base made up of upper and lower porcelains 5 and 6 connected by through screws 7, said base mounting the usual screw shell lamp 65 contact 8 and center contact 9 and carrying also the frame 10 in which the spindle 11 is journaled, the circuit terminals 13 and 14 and the contacts 15 and 16 on the upper and lower porcelains respectively for engagement 70 by the contact making arms of a spring yoke 12, said arms being forced into engagement with said contacts by a cam 17 on the spindle.

The operating spindle 11 is specially 75 constructed to enable the switch being assembled without a husk and so as to enable the operating key being connected therewith after such assemblage in the husk. For this purpose the spindle is fore-shortened, 80 usually to such an extent as to just about extend through the inclosing shell 18 of the socket and it is furthermore formed with an angular sided socket 19 in the exposed end thereof to receive a similarly shaped 85 protruding angular sided stem 20 on the detachable operating key 21. In practice this shortened stub spindle is formed with an enlargement or head 22 at the outer or exposed end thereof and the angular sided socket 19 90 is formed in this head. A simple method of making this special spindle is to turn down the spindle out of stock the size of the head, leaving the head portion the original diameter of the stock, then to drill a cylindrical socket in the end of the head and then, after inserting an anvil of the required shape into this socket, to flatten down one side of the socket. This provides a simple 95 and strong one-piece spindle which can be 100 produced on ordinary turning and forming machines at small cost.

The detachable operating keys are usually made with the projecting angular sided stem 20 long enough to answer for all the different sizes of husks in use, so that they may be used with the largest sized husks without change and may, if desired, be shortened to make a close fit with the husks of the smaller sizes. In Fig. 1 I have illustrated a husk 110

23 of fairly large size adapted to take the full length key, said key being shown as having a protruding stem 20 of considerable length. This stem is preferably covered by 5 an insulating bushing 24 which is cut to the proper length and slipped over the stem so as to cover the gap between the base of the key at 25 and the end of the stub spindle. The socketed end of the spindle also is preferably covered by an insulating collar 26, the insulating bushing and collar usually meeting to form an insulating cover over 10 the thus-extended spindle. When the stem of the detachable key is shortened to adapt 15 the key for smaller husks, the insulating bushing 24 may be shortened accordingly and in some cases where the key is considerably shortened, the bushing may be entirely omitted as is the case in Fig. 3, the 20 end face 25 of the key, which ordinarily is of insulating material, abutting against the socketed end of the spindle to complete the insulating covering over the spindle.

The upper circuit terminal 13 is shown 25 provided with an angularly inturned foot portion 27 by which it is secured to the upper porcelain through the medium of a screw 28 and the upper contact 15 is shown of special construction, it being made of 30 spring material spaced away from the face of the porcelain so as to be capable of yielding toward the same and having a foot portion 29 engaged and held beneath the foot portion 27 of the circuit terminal. This 35 yielding contact provides an automatic adjustment which prevents breakage or damage to the parts. The porcelains in particular vary more or less in size so that in some instances if no other provision were made 40 the cam 17 might have a tendency in its spreading operation to break the porcelains or cause other damage but with this form of contact the cam forces the arms of the spring yoke into engagement with the contacts provided therefor and if a further 45 spreading action is necessary due to misfit of the parts for instance, such further movement is taken up by the yielding spring contact 15. A firm electrical contact is 50 therefore assured without the liability of breakage or injury of the parts.

It will be apparent from the foregoing that my invention is entirely practical and desirable, a special advantage being that

Copies of this patent may be obtained for five cents each, by addressing the "Commissioner of Patents, Washington, D. C."

with this invention it is only necessary to keep in stock the one size of operating key and if necessary or desirable, to cut down the stem of the operating key and the insulating bushing therefor to suit particular fixtures. The stem of the key is made to fit the socket therefor sufficiently tight to hold under normal conditions and the proper fit of the parts is facilitated by making the stem or the socket on a slight taper, the parts being assembled with a light driving blow which causes the key stem to be engaged friction-tight with the operating spindle. 55 60 65 70

I claim:

1. In combination, a key switch having an operating spindle provided with an angular-sided socket in the end thereof, an operating key having an angular-sided stem frictionally engaged in said socket, and an insulating covering over said joint between the spindle and detachable key. 70

2. In combination with a key switch having an operating spindle provided with an angular-sided socket in the exposed end thereof, a detachable key having an angular-sided stem frictionally engaged in said socket, an insulating collar on the spindle surrounding the socket portion in the end thereof, and an insulating bushing on the stem abutting said insulating collar on the spindle. 80

3. In combination, a key socket switch having a stub spindle provided with an angular-sided socket in the exposed end thereof, an insulating collar covering said socketed end portion of the stub spindle, a detachable key having a lengthened protruding angular-sided stem for engagement with the socket, and an insulating bushing cut to fit the length of stem between the base of the key and the end of the stub spindle. 90

4. A key socket switch having a stub spindle provided with an enlarged head at its outer end, and an angular-sided socket in said head, a detachable key having an angular-sided stem engaged in the socket to form a continuation of the spindle, said stem and socket having a tapered fit whereby said parts may be forced together to frictionally interlock the same, and an insulating covering on the spindle thus formed. 100

CHARLES W. BROOKETT
